SASH BALANCE

August Viehweger, Richford, N. Y., assignor to
Grand Rapids Hardware Company, Grand
Rapids, Mich.

Application November 5, 1943, Serial No. 509,033

14 Claims. (Cl. 16—197)

This invention relates to improvements in sash balances.

The main objects of this invention are:

First, to provide a sash balance which is simple and economical in structure and which may be readily installed by comparatively unskilled workmen.

Second, to provide a sash balance in which the tension of the spring element may be easily and accurately adjusted for the requirements of the particular installation.

Third, to provide a sash balance which has a wide range of adaptability of load as well as of installation.

Fourth, to provide a sash balance of the spring type which is substantially noiseless in operation.

Further objects relating to details and economies of construction and operation will appear from the description to follow. The invention is defined in the claims. A structure embodying the features of my invention is illustrated in the accompanying drawing, in which:

Fig. 1 is a fragmentary view of an installation of sash balance embodying my invention, the casing and the window being partially broken away and sectioned, and the casing of the balance being partially broken away and in longitudinal section on line 1—1 of Fig. 6.

Fig. 2 is an enlarged fragmentary view corresponding to that of Fig. 1, with the window in open position.

Fig. 3 is a fragmentary view partially broken away and partially in longitudinal section on the broken line 3—3 of Fig. 5.

Fig. 4 is an enlarged exploded view showing details of various parts of the balance.

Fig. 5 is a fragmentary horizontal section taken on line 5—5 of Fig. 3.

Fig. 6 is a fragmentary plan view of a window embodying a pair of sash balances.

Fig. 7 is a perspective view of the pulley block or guide element.

In the embodiment of my invention illustrated in the accompanying drawing, 1 represents a window casing and 2 a window sash slideable therein. The window sash is longitudinally grooved at 3, preferably in both vertical edges thereof, although sometimes a single sash balance is employed, and as the sash balances are duplicates only one will be illustrated and described.

My improved sash balance comprises a tubular casing 4 having a longitudinal slot 5 therein. One end of this casing is provided with a plug-like closure 6 which is secured by indenting por-

tions of the casing 7 into recesses 8 of the plug. The casing and plug have registering holes receiving the attaching screw 9. A tubular ratchet member 10 is inserted into the other end of the casing and is secured therein by indenting opposed portions 11 of the casing into recesses 12 provided therefor in the ratchet member. This provides opposed transverse notched or slot-like recesses 13 adapted to receive the arms of the staple 14 which coact with the screw 9 in anchoring the casing within the groove of the sash.

A tubular adjusting or spring tension member 15 is rotatably and axially movable within the ratchet member 10, the member 15 being notched at 16 to receive an adjusting tool. The movable ratchet member 17 is sleeved upon the member 15 and fixedly secured thereto by upsetting the ratchet member and the adjusting member, as indicated at 18. This upset provides an internal shoulder 19 with the adjusting member which serves as a support for the anchoring member 20 of the cable 21. The cable 21 is roved or passed around the pulley 22 of the pulley block 23, which is slidable within the casing and provided with a lug 24 slidably within the slot, thus preventing rotative movement of the pulley block. The cable terminates in a loop 25 adapted to receive a screw 26 by which it may be attached to the casing, as illustrated in Fig. 1.

The coiled compression spring 27 is housed within the casing, being preferably a reasonably close fit therein, the lower end of the casing being in supported engagement by the thrust block 28 superimposed on the pulley block. The spring terminates in a longitudinal extension 29 arranged through a hole 30 in the thrust member 28 to engage a hole 31 in the pulley block, thus anchoring the spring against rotative movement as well as delivering the thrust of the spring 27 against the pulley block. Some of the terminal coils 32 of the other end of the spring are in clutching engagement with the portion of the adjusting member projecting inwardly of the clutch member 17, which constitutes a thrust shoulder for the spring.

To prevent kinking and possible overlapping of the coils of the spring, I provide a tubular rod 33 which frictionally fits within the intermediate coils of the spring, thus supporting the rod with its ends in spaced relation to the thrust block 28 and the inner end of the adjusting member. This permits collapsing of the spring as the pulley block is actuated against the tension of the spring as results from movement of the window to its closed position, as shown in Fig. 1.

The stored tension in the spring resulting from the adjustment of its adjusting member and this collapsing serve to effectively counterbalance the window. Tension of the spring can be adjusted for windows of widely varying sizes and weight merely by means of a tool, and after the balance has been mounted in the window.

In the accompanying drawing I have illustrated the structure installed with the balance casing in the window. It will be understood that the parts can be reversed; however, the installation illustrated is preferred by me. My improved balance is very simple and economical in its parts in the assembly thereof and can be installed by relatively unskilled workmen and can be readily adjusted to effect the desired counterbalancing action. I have illustrated and described an embodiment which I consider highly practical. I have not attempted to illustrate or describe certain modifications or adaptations, as it is believed this disclosure will enable those skilled in the art to embody or adapt the invention as may be desired.

Having thus described my invention, what I claim as new and desire to secure by Letters Patent is:

1. In a sash balance the combination of a longitudinally slotted tubular casing, a plug fixed in one end of said casing, said casing and plug having registering holes adapted to receive an attaching screw, a tubular fixed ratchet member secured within the other end of said casing by opposed indentations in the casing, which indentations constitute recesses for the prongs of an attaching staple, a tubular adjusting member axially and rotatably adjustable in said fixed ratchet member, an adjustable ratchet member sleeved upon said adjusting member in spaced relation to the ends thereof and having ratchet teeth coacting with the teeth of said fixed ratchet member, said ratchet member being secured to said adjusting member by indentations resulting in internal shoulders within said adjusting member, a pulley block slideable in said casing and provided with a lug engaging said slot thereof, a coiled spring having one end thereof in clutching engagement with the inner end of said adjusting member and abutting the said ratchet member thereof, the other end of said spring being thrustingly associated with and terminating in an extension engaging said pulley block, and a cable roved around the pulley of said pulley block and disposed longitudinally through said spring, the inner end of said cable being provided with an anchoring block rotatively engaging said shoulder within said adjusting member, the outer end of said cable being provided with attaching means.

2. In a sash balance the combination of a longitudinally slotted tubular casing, a plug fixed in one end of said casing, a tubular fixed ratchet member secured within the other end of said casing, a tubular adjusting member axially and rotatably adjustable in said fixed ratchet member, an adjustable ratchet member fixed upon said adjusting member in spaced relation to the ends thereof and having ratchet teeth coacting with the teeth of said fixed ratchet member, a pulley block slideable in said casing and provided with a lug engaging said slot thereof, a coiled spring having one end thereof in clutching engagement with the inner end of said adjusting member and abutting the said ratchet member thereof, the other end of said spring being thrustingly associated with and terminating in an ex-

tension engaging said pulley block, and a cable roved around the pulley of said pulley block and disposed longitudinally through said spring, the inner end of said cable being provided with an anchoring block within said adjusting member, the outer end of said cable being provided with attaching means.

3. In a sash balance the combination of a longitudinally slotted tubular casing, a plug fixed in one end of said casing, a tubular fixed ratchet member secured within the other end of said casing, a tubular adjusting member axially and rotatably adjustable in said fixed ratchet member, an adjustable ratchet member fixed upon said adjusting member in spaced relation to the ends thereof and having ratchet teeth coacting with the teeth of said fixed ratchet member, a pulley block slideable in said casing and provided with a lug engaging said slot thereof, a coiled spring having one end thereof in clutching engagement with the inner end of said adjusting member and abutting the said ratchet member thereof, the other end of said spring being thrustingly associated with and terminating in an extension engaging said pulley block, a tubular rod arranged centrally within said spring in supporting engagement with intermediate coils thereof and with its ends in spaced relation to the inner end of the adjusting member and said pulley block, and a cable roved around the pulley of said pulley block and disposed longitudinally through said spring and rod therein, the inner end of said cable being provided with an anchoring block within said adjusting member, the outer end of said cable being provided with attaching means.

4. In a sash balance the combination of a longitudinally slotted tubular casing, a plug fixed in one end of said casing, a tubular fixed ratchet member secured within the other end of said casing, a tubular adjusting member axially and rotatably adjustable in said fixed ratchet member, an adjustable ratchet member fixed upon said adjusting member in spaced relation to the ends thereof and having ratchet teeth coacting with the teeth of said fixed ratchet member, a pulley block slideable in said casing and provided with a lug engaging said slot thereof, a spring thrust member seated on said pulley block, a coiled spring having one end thereof in clutching engagement with the inner end of said adjusting member and abutting the said ratchet member thereof, the other end of said spring being thrustingly associated with and terminating in an extension engaging said pulley block, a tubular rod arranged centrally within said spring in supporting engagement with intermediate coils thereof and with its ends in spaced relation to the inner end of the adjusting member and said pulley block, and a cable roved around the pulley of said pulley block and disposed longitudinally through said spring and rod therein, the inner end of said cable being provided with an anchoring block within said adjusting member, the outer end of said cable being provided with attaching means.

5. In a sash balance the combination of a longitudinally slotted tubular casing, a tubular fixed ratchet member within said casing, an adjusting member axially and rotatably adjustable in said fixed ratchet member and provided with ratchet teeth coacting with the teeth of said fixed ratchet member, a cable guide member housed within said casing and slidably engaging said slot thereof, a coiled compression spring having one end

thereof connected to said adjusting member and the other in thrust relation to said guide member, a tubular rod arranged centrally within said spring in supporting engagement with intermediate coils thereof and with its ends in spaced relation to the inner end of the adjusting member and said guide member, and a cable roved around said guide member and disposed longitudinally through said spring and rod therein, the inner end of said cable being anchored to said adjusting member.

6. In a sash balance the combination of a longitudinally slotted tubular casing, a tubular fixed ratchet member within said casing, an adjusting member axially and rotatably adjustable in said fixed ratchet member and provided with ratchet teeth coacting with the teeth of said fixed ratchet member, a cable guide member housed within said casing and slidably engaging said slot thereof, a coiled compression spring having one end thereof connected to said adjusting member and the other in thrust relation to said guide member, and a cable disposed around said guide member and disposed longitudinally through said spring, the inner end of said cable being anchored to said adjusting member.

7. In a sash balance the combination of a longitudinally slotted tubular casing, a fixed ratchet member at one end of said casing, a tensioning member including an adjustable ratchet member coacting with said fixed ratchet member, a cable guide member housed within said casing and slidably engaging said slot thereof, a coiled spring having one end thereof connected to said tensioning member and the other in thrust relation to said guide member, a tubular rod arranged within said spring in supporting and supported engagement with intermediate coils thereof and with its ends spaced from the ends of the spring when the spring is in extended position, and a cable disposed longitudinally within said spring and rod, anchored at its inner end and roved around said cable guide member.

8. In a sash balance the combination of a longitudinally slotted tubular casing, a fixed ratchet member at one end of said casing, a tensioning member including an adjustable ratchet member coacting with said fixed ratchet member, a cable guide member housed within said casing and slidably engaging said slot thereof, a coiled spring having one end thereof connected to said tensioning member and the other in thrust relation to said guide member, and a cable disposed longitudinally within said spring, anchored at its inner end and roved around said cable guide member.

9. In a sash balance the combination of a longitudinally slotted tubular casing, a cable guide element slidable within said casing and slidably engaging said slot, a compression spring disposed within said casing in thrust relation to said cable

guide element, ratchet means for tensioning said spring, said spring acting to normally engage said ratchet means, and a cable roved over said guide element and anchored within said casing.

5 10. In a sash balance, the combination of a support, a fixed ratchet member at one end of said support, a tensioning member including an adjustable ratchet member coacting with said fixed ratchet member, a cable guide member slidably and non-rotatably carried by said support, a coiled spring having one end thereof connected to said tensioning member and its other end anchored to and in thrust relation to said cable guide member, and a cable disposed around said guide member and extending within said spring, the inner end of said cable being anchored, its outer end being provided with attaching means.

15 11. In a sash balance the combination of a casing, a coiled compression spring housed within the said casing, a cable guide element slidable within said casing and in thrust engagement with one end of said spring, means for supporting and tensioning the other end of said spring housed within said casing, and a cable disposed within and longitudinally of said spring and anchored at its inner end and roved over said guide member.

20 12. In a sash balance the combination of a support, a coiled compression spring axially supported at one end on said support, a cable guide element slidable on said support and in thrust engagement with the other end of said spring, means for tensioning said spring, said spring tensioning means including means for anchoring one end of said spring against rotation and rotatably adjusting the opposite end of said spring, and a cable disposed longitudinally of said spring and anchored at its inner end and roved over said guide member.

25 13. In a sash balance the combination of a support, a coiled compression spring axially supported at one end on said support, a cable guide element slidable on said support and in thrust engagement with the other end of said spring, and a cable disposed within and longitudinally of said spring and anchored at its inner end and roved over said guide element.

30 14. In a sash balance the combination of a support, a cable guide element slidable longitudinally of said support, a coiled compression spring disposed in thrust relation to said cable guide element, means for tensioning said spring, said spring tensioning means including means for anchoring one end of said spring against rotation and rotatably adjusting the opposite end of said spring, and a cable roved over said guide member and having its inner end anchored to said support and its outer end extending from said guide means for attachment to a window or its casing.
